METHOD OF MAKING A MOUNT STRUCTURE
FOR FLASH LAMPSRobert M. Anderson, Euclid, Ohio, assignor to General
Electric Company, a corporation of New York
Filed Nov. 12, 1959, Ser. No. 852,552
1 Claim. (Cl. 67—31)

My invention relates to photographic flash lamps of the type comprising a sealed bulb or envelope containing a combustion-supporting atmosphere and a loosely arranged filling of metallic combustible material which is ignited by an ignition means comprising a fulminating primer and a filament or heater element adapted to set off the primer. More particularly, my invention relates to the method of manufacture of the ignition means for such type flash lamps.

Conventional type flash lamps in common use at present are provided with ignition means customarily comprising a filament consisting of a short straight length of fine tungsten wire, usually having an effective lighted length of the order of 50 to 65 mils, which is connected substantially straight across the inner ends of a pair of generally side-by-side lead-in wires sealed into one end of the bulb. The filament is energized and heated, usually by a dry cell battery connected across the lead-in wires, to thereby ignite a fulminating primer coated on the inner ends of the lead-in wires at their connections or junctions with the filament. The ignited primer then ignites, in turn, a filling of filamentary metallic combustible material the ensuing combustion of which then produces a momentary flash of light of high intensity.

The assembly of the filament, its supporting lead-in wires, and the primer coatings on the inner ends of the lead-in wires, together comprise what is commonly known as the mount structure of the lamp. In the manufacture of the lamp, the mount structure is sealed into the bulb in a position in which the filament and the associated primer coatings or beads are located within the filling of combustible material in the bulb so as to be more or less surrounded thereby and thus in effective ignition range relative thereto. To this end, it is the general practice to first introduce the combustible filling material into and distribute it within the bulb and to then insert the lamp mount, filament end first, into the open neck end of the bulb and into sealing position therein, with the filament and primer coatings of the mount located within the filling of combustible material. With such procedure, however, because of the comparatively appreciable spacing between the primer coatings or beads on the lead-in wires of flash lamps as conventionally made heretofore, and also the substantially taut condition of the ignition filament between the primer beads, some of the strands of the filamentary combustible filling material within the lamp bulb are usually trapped in and enter the space between the primer beads or coatings during the insertion of the mount into the bulb, and come in contact with and firmly press against the substantially taut ignition filament which extends more or less straight across the opening between the two primer beads. The strands of combustible material thus in contact with the taut filament then exert a cooling effect thereon during the energization and heating of the filament to set off the primer. This cooling effect on the filament is sufficient in some cases, as when the dry cell batteries are weak or the circuit contacts are poor, to prevent the filament from attaining a temperature high enough to ignite the primer, with the result that the lamp fails to flash. The flashability of the lamp thus is adversely affected by the contact of the ignition filament with the combustible material present within the lamp bulb.

Moreover, the pressure of the combustible material

2

against the fine tungsten wire filament with which it is in contact is also apt to cause elongation of the filament during the time it is heating up. The resulting reduction in the cross-sectional area of the filament, and the corresponding increase in its electrical resistance at the region of reduced cross-sectional area, therefore tends to cause either the burn-out of the filament at such region of reduced cross-sectional area, or a severing or pulling apart of the filament at such region, so that the lamp again fails to flash.

It is an object, therefore, of my invention to provide a method of making a mount structure for use in a flash lamp of the above mentioned character having improved flashability characteristics and greater freedom from filament burn-out, from lamp to lamp.

Another object of my invention is to provide a flash lamp of the above mentioned character having an ignition filament located within but uniformly out of firm contact with the filamentary combustible material, from lamp to lamp.

Still another object of my invention is to provide a flash lamp of the above mentioned character having a lamp ignition mount structure of such a construction as to prevent firm contact of the ignition filament with the surrounding filamentary combustible material within the lamp bulb in substantially all cases.

A further object of my invention is to provide a novel method of making a flash lamp of the above mentioned character so as to effectively prevent the filamentary combustible material from firmly contacting the ignition filament positioned therewithin.

Briefly stated, in accordance with one aspect of my invention, the primer-coated inner ends of the lead-in wires of conventional type lamp ignition mounts such as have been customarily used heretofore in flash lamps, across which lead-in wire ends the ignition filament is connected in a substantially taut condition, are bent toward one another, prior to the insertion of the mount into the lamp bulb for sealing thereto, until the primer coatings or beads of the mount practically touch one another, thereby not only materially decreasing the space between the primer beads so as to minimize the chance of entrance of the filamentary combustible material thereinto and into contact with the ignition filament, but also forming the taut filament into an open loop shape between the primer beads so as to have an appreciable amount of slack therein and thus be readily displaceable, in the event it should be actually contacted by the combustible material, whereby to obviate firm pressure contact therebetween in the completed lamp.

Further objects and advantages of my invention will appear from the following detailed description of a species thereof and from the accompanying drawing.

In the drawing, FIG. 1 is an elevation of a flash lamp comprising my invention, and

FIG. 2 is a fragmentary elevation, on a greatly enlarged scale, of the ignition means or mount structure of the flash lamp comprising my invention.

Referring to the drawing, the flash lamp there shown comprises a sealed light-transmissive envelope or bulb 1 which may be formed of glass and contains a filling of a combustion-supporting gas such as oxygen and a loosely arranged filling of filamentary metallic combustible material 2 of a composition such as zirconium, aluminum or aluminum-magnesium alloy which is of a readily combustible character when in a finely divided or filamentary state. As shown, the combustible material 2 may be in the form of fine wire, ribbon, or other filamentary character such as that commonly known as shredded foil, the individual strands of the filamentary material having a cross-sectional area of the order of one square mil.

Sealed into the neck end 3 of the envelope or bulb 1

is a lamp ignition means or mount structure 4 comprising a glass stem tube 5 extending into the envelope or bulb 1 and terminating at its inner end in a flattened stem press portion 6 through which are sealed a pair of lead-in wires 7. As shown, the said lead-in wires 7 extend from the flattened stem press 6 into the interior of the envelope or bulb 1 in more or less side-by-side relation and they are bridged at their inner ends by a filament 8 in the form of a straight length of fine tungsten wire, usually of 1 mil or less diameter, connected to the respective lead-in wires 7 and located within the filling of combustible material 2 so as to be in effective ignition relation thereto. The filament 8 has an effective lighted length, between its connections to the lead-in wires, of approximately 55 to 60 mils such as has been customary heretofore. The inner ends of the lead-in wires 7, at their junctions or connections with the ignition filament 8, are provided with thin coatings or beads 9 of a suitable primer or fulminating material such as a mixture of zirconium, magnesium and potassium perchlorate powders bonded together by a suitable binder such as a 2-5% solution of nitrocellulose in amyl acetate. Externally of the envelope or bulb 1, the lead-in wires 7 are respectively connected to the end contact 10 and the side shell contact 11 of a conventional type lamp base 12 suitably secured to the neck and 3 of the envelope, as by the conventional basing cement (not shown). The envelope or bulb 1 may be exhausted and filled with oxygen or other combustion-supporting gas in the conventional manner through an exhaust tube 13 extending from the stem press 6 of the lamp mount 4 and communicating with the interior of the envelope through a side aperture 14 in the stem press. After evacuation of the envelope 1 and the introduction of the gas filling therewith, the exhaust tube 13 is tipped-off in the well known manner to thereby hermetically seal the envelope.

So far as known, the primer-carrying inner ends or tips of the lead-in wires of prior type flash lamps have all been spaced an appreciable distance apart as compared to the cross-sectional size (around 1 square mil or so) of the individual strands of the combustible material 2, the lead tip spacing "a" (FIG. 2) ordinarily amounting to at least 50 mils between the inner facing sides of the wires. In addition, the ignition filaments of such lamps have all been connected substantially straight across the said lead tips or inner ends of the lead-in wires so as to be practically taut therebetween. Thus, in the commercial designated No. 5 flash lamp, for example, manufactured by applicant's assignee, the inner lead tip spacing "a" has customarily amounted to approximately 55 mils, and the effective or lighted length of the filament (i.e., the length thereof between its connections to the inner lead tips) has amounted to around 58 mils, the inner lead tip spacing customarily being made a few mils, i.e., 3 mils or so, shorter than the desired lighted length of the filament in order to provide a slight amount of slack in the filament for the purpose of insuring against tensioning and resultant breakage of the fragile filament by tensile forces that otherwise may be applied thereto by the lead-in wires as, for instance, by their vibration during the handling or shipment of the lamps. Moreover, the primer coatings on the lead tips of prior type flash lamps have all been of such a thickness, usually amounting to around 5 mils or less in coating thickness, to produce a spacing "b" therebetween at their inner facing sides of at least 40 mils, which distance obviously is comparatively large compared to the usual 1 mil or so cross-sectional size of the strands of combustible material 2.

Because of such customary relatively wide spacing of the primer coatings or beads 9 in prior type flash lamps, therefore, there is considerable likelihood of some of the strands of the combustible filling material 2 in the lamp bulb becoming trapped between the primer coatings or beads 9 and coming into contact with the substantially taut ignition filament extending therebetween, during the insertion of the lamp mount 4 into the lamp bulb for

sealing therewith. The strands of combustible material thus in contact with the ignition filament are not only likely to exert a cooling effect thereon such as to in some cases prevent the filament from heating to a temperature sufficient to set off the primer, thus impairing the flashability of the lamp, but they also may act to apply sufficient tension to the substantially taut filament to in some instances result in elongation thereof and corresponding reduction in its cross-sectional area such as to cause either the burn-out of the filament or a severing or pulling apart thereof, thus rendering the lamp inoperative.

In accordance with the invention, to prevent or minimize as much as possible the entry of any strands of the combustible material 2 into the space between the primer beads 9 and into firm contact with the ignition filament 8 extending therebetween, during the insertion of the lamp mount 4 into the bulb 1 for sealing therewith, with consequent elimination of the disadvantages resulting therefrom such as enumerated above, the primer coatings or beads 9 of the lamp mount 4 are positioned as close as possible to one another, within practical manufacturing limits, so as to practically touch one another, as clearly shown in FIG. 2. In addition, the portions of the ignition filament 8 bridging and exposed between the primer beads or coatings 9 is formed into an open loop shape, as clearly shown in FIG. 2, so as to have an appreciable amount of slack therein. For the purposes of the invention, the primer beads 9 are located so that their facing inner sides are spaced apart a distance "b" of less than 40 mils, and preferably as close as 15 to 25 mils to one another, at least at one region thereof between their innermost tip ends and the points where the ignition filament 8 emerges from the said primer beads.

By reducing the spacing between the primer coatings or beads 9 to the point where they practically touch one another, the field or area within which strands of the combustible material 2 are apt to be caught or trapped in the entrance opening between the primer beads and brought into contact with the ignition filament 8, during the insertion of the lamp mount 4 into the bulb 1 for sealing therewith, is correspondingly reduced to a degree such as to practically eliminate the likelihood of any such strand entering the said opening between the primer beads and contacting the ignition filament. Moreover, the formation of the ignition filament 8 into open loop shape between the primer beads 9 so as to have an appreciable amount of slack therein permits the filament, in most cases, to give way or yield to any pressure that may be exerted thereon by any strand of combustible material 2 that actually may enter the space between the primer beads 9 during the insertion of the lamp mount 4 into the lamp bulb 1, thereby minimizing the likelihood of such strand of combustible material contacting the ignition filament with sufficient pressure to exert a material cooling effect thereon or to cause an elongation and resultant severance of the filament during the energization thereof to set off the lamp.

The primer bead and ignition filament arrangement according to the invention may be conveniently produced simply by bending toward one another the inner end portions of the lead-in wires of conventional type flash lamp mounts such as have been customarily employed heretofore in flash lamps, the said lead-in wire portions being bent toward one another until the primer coatings or beads 9 practically touch one another. In other words, a conventional ignition mount is first formed in the customary manner by sealing a pair of lead-in wires 7 into a glass support member such as the stem tube 5, with the inner tip ends of the lead-in wires located alongside one another and spaced apart a comparatively wide distance of at least 50 mils between their facing inner sides such as has been customary heretofore, and then stretching a wire filament straight across and connecting it to the inner tip ends of the lead-in wires so as to have an effective or lighted length therebetween

a few mils greater, i.e., 3 or so mils greater, than the said lead-in wire spacing. The primer coatings or beads 9 are then formed on the lead-in wires 7 by dipping the inner tip ends thereof and the ignition filament 8 connected therebetween in a suspension of the primer material. After the coatings or beads 9 of primer material have dried on the lead-in wires, the inner end portions of the said wires are then bent or bodily shifted toward one another to reduce the spacing "b" between the primer beads 9 to a distance less than 40 mils, and preferably to the point where they nearly touch one another. It is desirable, however, not to bend the lead-in wires so far toward one another as to cause the primer beads 9 to actually contact each other, in order to avoid the possibility of the primer bead material being chipped or knocked off the lead-in wires. The bending together of the lead-in wires 7 to close the gap between the primer beads 9 automatically causes the substantially taut filament 9 extending therebetween to buckle and transform itself into open loop shape so as to have the desired appreciable amount of slack therein. By forming the lamp mount structure 4 comprising the invention in the above described manner, the customary desired effective lighted filament length of between 50 to 65 mils, which has been determined to be the optimum length for proper ignition of flash lamps from the customary power sources employed for such purpose, is at the same time maintained.

Flash lamps provided with ignition mounts 4 constructed in accordance with the invention possess marked superiority in their flashability characteristics, and in their freedom from filament burn-outs without the lamps flashing. Thus, tests have conclusively shown that, for flash lamps having ignition mounts as heretofore constructed, the number of lamps that will fail to flash, when connected to a conventional electrical power source of approximately 35 1.1 amperes for a duration of 2 milliseconds circuit closure time, will ordinarily amount to around 30 lamps out of approximately 2400 lamps tested. In contrast thereto, in corresponding tests of identical type flash lamps except provided with ignition mounts 4 according to the 40 invention, there were no failures to flash at all out of approximately 1100 lamps tested. Such complete elimination of all failures to flash when the lamps are connected

to conventional electrical power supplies is, of course, a most important and highly desirable feature of the invention since it establishes the reliability of the flash lamp to operate.

5 Although a preferred embodiment of my invention has been disclosed, it will be understood that the invention is not to be limited to the specific construction and arrangement of parts shown, but that they may be widely modified within the spirit and scope of my invention as defined by the appended claim. Thus, instead of the primer-carrying inner end portions of the lead-in wires 7 extending in the same general direction as the remainder of such wires so as to extend more or less lengthwise of the bulb axis, they may be bent over to extend transversely to the bulb axis as shown in my U.S. Patent 2,729,-15 960, issued January 10, 1956 and assigned to the assignee of the present invention.

What I claim as new and desire to secure by Letters Patent of the United States is:

20 The method of making a mount structure for flash lamps which comprises sealing a pair of lead-in wires into a glass support member to position end portions of said wires alongside one another and spaced apart a distance of at least 50 mils, connecting a straight wire filament substantially taut across the said ends of said wires, applying coatings of primer material to the said ends of said wires at their junctions with the filament, and then bending the said wires toward each other to close the space between the said end portions thereof to a distance less than 50 mils and the space between the primer coatings thereon to a distance less than 40 mils and form the portion of the filament extending between said primer coatings into open loop shape.
